UNITED STATES PATENT OFFICE

169,009

FISH GAFF AND SPREADER OR SIMILAR
ARTICLE

Ramuald B. Locher, Royal Oak, Mich.

Application September 15, 1952, Serial No. 21,463

Term of patent 14 years

(Cl. D31—4)

To all whom it may concern:

Be it known that I, Ramuald B. Locher, a citizen of the United States of America, residing at the city of Royal Oak, county of Oakland, State of Michigan, United States of America, have invented a new, original, and ornamental Design for a Fish Gaff and Spreader or Similar Article, of which the following is a specification, reference being had to the accompanying drawing, forming a part hereof, wherein:

Fig. 1 is a side elevational view of a fish gaff and spreader or similar article, showing my new design;

Fig. 2 is a bottom plan view thereof; and

Fig. 3 is a top plan view thereof.

I claim:

The ornamental design for a fish gaff and spreader or similar article, substantially as shown.
RAMUALD B. LOCHER.
